UNITED STATES PATENT OFFICE

150,953

DESIGN FOR A HEAT FUSIBLE MATERIAL
SPRAY GUN

Herbert S. Ingham, Roslyn Estates, N. Y.

Application October 5, 1946, Serial No. 133,801

Term of patent 14 years

(Cl. D62—2)

To all whom it may concern:

I, Herbert S. Ingham, a citizen of the United States, residing at Roslyn Estates, county of Nassau, State of New York, have invented a new, original, and ornamental Design for Heat Fusible Material Spray Guns Such as of the Wire Feed Type, of which the following is the specification, reference being had to the accompanying drawings, forming a part thereof, in which:

Fig. 1 represents a side view of a heat fusible material spray gun showing my new design with the handle, controlling the flow of combustible and combustion supporting gas to the melting zone in the gun, shown in "lighting" position, i. e., in a partly opened position controlling the best mixture for lighting the gun;

Fig. 2 is a view of the opposite side of Fig. 1;

Fig. 3 is a front view thereof with the "lighting" handle in full open position;

Fig. 4 is a rear view thereof with handle in the same position shown in Fig. 3;

Fig. 5 is a top plan view of the gun with the handle in the position shown in Fig. 1;

Fig. 6 is a bottom plan view thereof with the handle in the position shown in Figs. 1 and 5;

Fig. 7 is a perspective view thereof taken from the top, rear and one side; and

Fig. 8 is a perspective view thereof taken from the top, front and other side with the handle in closed position.

I claim:

The ornamental design for a heat fusible material spray gun, substantially as shown.

HERBERT S. INGHAM.
